[57] CLAIM

The ornamental design for a shoe outsole, as shown and described.

DESCRIPTION

FIG. 1 is a bottom plan view of a shoe outsole showing my new design;

FIG. 2 is a side elevational view of one side of the shoe outsole shown in FIG. 1;

FIG. 3 is a side elevational view of the other side of the shoe outsole shown in FIG. 1;

FIG. 4 is a front elevational view of the shoe outsole shown in FIG. 1; and,

FIG. 5 is a rear elevational view of the shoe outsole shown in FIG. 1.

The top surface of the outsole is substantially plain. The broken line showing of a shoe upper in FIGS. 2 and 3 is for illustrative purposes and forms no part of the claimed design.
